George A. Deane, Inventor

By Dwight B. Gann, Attorney

UNITED STATES PATENT OFFICE

GEORGE A. DEANE, OF CATSKILL, NEW YORK

JOINT CLEARER

Application filed April 5, 1932. Serial No. 603,437.

This invention relates to joint clearers, and has particular application to means for preventing the flexible linings of containers becoming fouled with the hinged covers thereof.

The invention has particular reference to coffin or casket structures, wherein linings are provided for the interior of the coffin body as well as the cover thereof, the present invention providing means for at all times maintaining the lining in proper condition at the gap between the body of the coffin and the hinged lid thereof, and preventing the lining becoming fouled with the hinged joint in the closing operation.

A particular object of the invention is to provide means of an improved nature for accomplishing the foregoing results which may be applied to any coffin structure where-
20 in a hinged part is employed, which may be easily and quickly applied without the exercise of special skill or knowledge and which is wholly invisible when properly applied.

A further object of the invention is to pro-
25 vide a device for the accomplishment of the results stated which is of extremely simple and inexpensive construction, which is composed of but few simple and readily assembled parts, which is so constructed as to ob-
30 viate the possibility of breakage or derange-
ment, and which will prove fully adequate in accomplishing the results sought.

With these objects in view, together with others which will appear as the description
35 proceeds, the invention consists in the novel construction, combination and arrangement of parts, all as will be described more fully hereinafter, illustrated in the drawing, and particularly pointed out in the claims.

40 In the drawing:—

Fig. 1 is a fragmentary sectional view taken through a portion of the casket body and the lid thereof adjacent a hinge connection, and illustrating the application of a device
45 of my invention in the position it will assume when the cover has been moved to full open position.

Fig. 2 is a similar view showing the parts in the position assumed when the cover is
50 closed, and

Fig. 3 is a detail perspective view of the attachment removed from the coffin structure.

Referring now more particularly to the drawing, 4 indicates the side wall or body portion of a conventional form of coffin, and 5 indicates the cover thereof; a hinge 6 of conventional form being shown as an element effecting a pivotal connection between the body and the cover. 7 indicates the lining of the coffin, which usually is of fine fabric such as silk or satin, secured in any approved manner to the interior of the cover thereof. The fabric extends in a continuous piece usually from the body across the hinge gap and into the cover, being loose so as to provide a fold at 8 to permit of the cover being swung to full open position without stretching or breaking the fabric.

In order to prevent the loose portion or fold 8 from becoming inserted or fouled between the hinged edges of the body and top when the latter is moved to closed position, a guard 9 is provided. This guard consists essentially of an articulated member associated between the body and the cover in such manner as to bridge the gap between them during all movements of the cover and to hold the lining away from the joint, whether the cover be in open or closed position. More particularly, the guard consists in leaves or links 10—11, preferably of identical length, hinged together as at 12 at adjacent ends. The outer extremities of the leaves are hinged or pivoted to anchor members 13 in the form of plates secured in any preferred manner to the interior of the body and cover respectively.

In practice, the articulated members of any desired or required numbers are applied to the casket along the hinged edge thereof. The anchor members will be so secured to the respective body and cover members as to dispose the hinge connections thereof in substantially the same horizontal plane with the hinge of the cover. The combined lengths of the leaves 10—11 is such as to exceed the gap between the body side and cover when the latter is in full open position. By constructing and assembling the lining guard in the

manner stated, the guard will arch the gap between the body and cover when the latter is open, thus preventing the lining from entering the gap. When the cover is moved 5 from open to closed positions the articulated member will describe an arc such as will prevent the lining from entering the gap, and upon completion of the closed movement, the articulated member will fold into the position 10 shown in Fig. 2.

As has been before stated, lining guards in any desired or required number may be employed, and, if desired, there may be provided on each of the articulated members 15 laterally projecting elements such as wires indicated at 14 in Fig. 3 to support the fabric. Such projecting members may be provided in any number and in any desired lengths.

While the foregoing is a description of the 20 invention as applied particularly to caskets or coffins, it will nevertheless be understood that the inventive idea may with equal success be employed with other structures wherein it is desired to prevent fouling of a flexible lining extending from the body portion of 25 the receptacle to the cover thereof.

Having thus described my invention, I claim:

1. In a coffin construction, a body side, a 30 top joined thereto, a continuous flexible liner connecting the interior of the side and top, and means associated between the side and top beneath said liner serving to bridge the joint between the side and top.

2. In a coffin construction, a body side, a 35 top hinged at one edge thereto and a flexible liner extending from the interior of the side to the top and providing a loose fold at said edge, a guard comprising a pair of leaves 40 hinged together at adjacent ends, and the outer ends of said leaves hinged respectively to the side and top beneath said fold.

3. In a coffin construction, a body side, a 45 top hinged thereto, a flexible liner connecting the interior of the side and top, a guard comprising a pair of leaves hinged together at adjacent ends, and the outer ends of said leaves hinged respectively to said side and top adjacent to the hinged edges of the latter and disposed beneath the liner.

4. In a coffin construction, a body side, a 50 top hinged thereto, a continuous flexible liner connecting the interior of the side and top and providing a loose fold at the juncture of the side with the top, a guard comprising a pair of leaves hinged together at adjacent ends and of a combined length greater than the breadth of the gap at the hinged connection of the side with the top when the latter 55 is in open position, and the outer ends of said leaves hinged respectively with the top and side beneath said liner.

5. In a coffin construction, a body side, a 60 top, a hinge connecting said body and top, a 65 flexible liner connecting the interior of the

side and top and providing a loose fold spanning the hinged connection, a guard comprising a pair of leaves hinged together at adjacent ends, and the outer ends of said leaves pivoted respectively to the side and top beneath said fold providing pivotal connection adjacent said hinge; the pivotal connection of one of said leaf ends being further removed from said hinge than the other.

In witness whereof, I have hereunto affixed 70 my signature.

GEORGE A. DEANE.
